UNITED STATES PATENT OFFICE.

JUSTIN HIPPOLYTE SIMÉON JECHOUX, OF VERRI NOIRE, FRANCE.

PERSPECTOGRAPH.

SPECIFICATION forming part of Letters Patent No. 499,387, dated June 18, 1893.

Application filed October 10, 1892. Serial No. 448,463. (No model.) Patented in France April 22, 1892, No. 220,997.

To all whom it may concern:

Be it known that I, JUSTIN HIPPOLYTE SIMÉON JECHOUX, tutor, a citizen of the French Republic, residing at Verri Noire, (Loire,) in the Republic of France, have invented a certain new and useful Perspectograph, (for which I have obtained Letters Patent in France, No. 220,997, dated April 22, 1892,) of which the following is a specification.

This invention relates to a perspectograph in which a telescope and a pencil are so mounted that the movements of the one are imparted to the other in such manner that when any given point of the object is viewed through the telescope, the position of the point of the pencil will indicate the corresponding position of such point on a plane horizontal surface such as a sheet of paper. By viewing various points of the object and marking the positions of such points on the drawing paper a correct perspective picture of the object can be obtained.

In the accompanying drawings Figure 1, is a front elevation of a perspectograph constructed in accordance with this invention. Fig. 2 is a section taken on the line a b of Fig. 1 looking in the direction of the arrow shown; and Fig. 3 is an enlarged detail view. The same letters of reference are used to denote the same or corresponding parts in all the figures.

The instrument is composed of three principal parts, a telescope a, a pencil b, and a slide c to which the telescope and the pencil are respectively connected by rods p and q. The slide c is made in the form of a loose collar capable of being slid on a horizontal rod d which latter is carried by a double collar i on a vertical standard h the foot j of which is firmly secured to the table or other plane horizontal surface t on which the drawing paper is placed. The double collar i is provided with two set screws or equivalent devices one of which serves to clamp the collar in any suitable position on the standard h while the other serves to clamp the horizontal rod d in any convenient position in the collar i thus providing for vertical and horizontal adjustment of the rod d. At one extremity of the horizontal rod d is fixed a segmental piece e slightly larger than a semi-

circle, in which are two diametrically opposite pins f and f', the outer one of which is formed on the end of a set screw, so that it may be 55 adjusted as required. The two pins f and f' are in a line with a prolongation of the axis of the horizontal rod d and between them support a circular ring g the periphery of which is provided with depressions or bushes in 60 which the pins f and f' take. To fix this ring g in position, the set screw pin f' is loosened, one of the bushes on the periphery of the ring is placed over the fixed pin f and the set screw is then tightened up causing its pin 65 f' to engage with the other peripheral bush and the ring is then capable of being turned about on the pins f and f' as a horizontal axis and without any side-play.

From the foregoing description it will be 70 seen (first) that the ring g is capable of rotation about a fixed diameter passing through the pins f and f' and coincides with the axis of the horizontal rod d; and (second) that the center of the ring g will occupy a constant position on the prolonged axis of the rod d whatever the position of the ring may be.

The telescope is composed of a cylindrical tube, the axis of which is determined partly by the center of an extremely small aperture 80 formed in a diaphragm placed on or over the eye-piece, and partly by the point of contact of two crossing threads placed in the objective. The telescope is rigidly secured to two exactly similar rods l and l' placed perpendicular to the axis of the telescope. To fix the telescope in position it is introduced into the ring g in such a manner that the extremities of the rods l and l' rest against two set screws m. The upper set screw m screws 85 from the outside completely through the thickness of the ring g as shown in Fig. 1, and in the detail view Fig. 3, while the lower set screw screws partially into the ring g from the interior of said ring, and carries a pin in 90 the center of its milled head, which pin rests against the extremities of the rod l'. The lower set screw cannot be passed from the outside through the thickness of the ring g on account of the saddle-piece o, the function of 95 which will be explained hereinafter. It will be seen that the telescope can rotate on a diameter passing through the set screws m, and rods l and l', and that this diameter is per-

pendicular to the diameter ff' of the ring g . It will also be seen that the center of the diameter which passes through the rods l and l' will coincide with the center of the ring g .

5 From the foregoing description it follows—(first) that the axis of the telescope can be directed toward any point of the object, and (second) that the center of the ring g will always occupy a fixed position in space. It is 10 in this fixed position that the eye of the observer is supposed to be placed and this fixed position then becomes the "point of view."

The pencil b is secured at the extremity of a cylindrical tube n into which slides another 15 tube n' of about equal length. An upper rod n'' slides into the inner tube n' and is connected to the saddle-piece o the sides of which are rigidly secured to two rings g' and g'' . These two rings g' and g'' are of the same 20 diameter as the ring g , and fit into annular spaces, one on each side of the said ring g as shown by the section view Fig. 3, in such a manner that the axes of the rings g' and g'' coincide. The rings g', g'' fit loosely in the 25 annular recesses, so that they are capable of rotation independently of the ring g and can move around their common axis through an angle of nearly one hundred and eighty degrees. They are maintained in position partly 30 by the saddle-piece o , and partly by circular flanges on the exterior of the ring g . From the preceding description it follows:—(first) that the axis of the pencil can be directed toward any point of the sheet of paper within 35 the limits of the drawing to be produced by the instrument, and that the point of the pencil can be made to touch this point on the paper; (second) that in whatever direction it may be placed the axis of the pencil will always 40 pass through the "point of view."

The slides c is formed of a single ring of any convenient length, which is adapted to glide smoothly over the tube d . It is connected to the telescope by a rod p and to the 45 saddle-piece o by another rod q . Those extremities of the rods p and q which are connected to the slides c are pivoted to the ends of two perpendicular diameters of a transverse vertical section of the slides. The other 50 extremity of the rod p is jointed to the telescope in such a manner as to be capable of turning round an axis perpendicular to the axis of the telescope; while the other extremity of the rod q is jointed to the saddle-piece 55 o so as to be capable of turning round an axis perpendicular to the axis of the pencil b . The two axes are equi-distant from the point of view.

It will be seen from the preceding statement:—(first) that the axis of the telescope lies in a plane passing through the axis of the rod d and with which it can make any desired angle; (second) that the axis of the pencil lies in another plane, also passing through 65 the axis of the rod d with which it can make any desired angle.; (third) that the two planes are perpendicular to each other in every po-

sition, as if one of the planes is turned around their line of intersection as a common axis, the other plane is caused to turn around the 70 same axis and to an equal extent; (fourth) that the angles formed by the axis of the telescope and the axis of the pencil with the axis of the tube d are adjacent and constantly equal; (fifth) that the axis of rotation of the 75 telescope is perpendicular to the axis of rotation of the pencil and that the axis of the rod d is perpendicular to each of the two others; (sixth) that the point of view, the point of the pencil, and the point where the axis of rotation of the rod q meets the axis of the tubes n and n' are always in the same 80 straight line.

To use the perspectograph, it is fixed by means of a catch or equivalent device on the 85 foot j to a horizontal table t before which the operator stands. The rod d is then so placed that its axis will be truly horizontal and actuated above the sheet of paper on which the drawing or perspective picture is to be made. 90 The drawing paper is firmly secured to the table t .

To obtain the perspective of any object the instrument is placed at a suitable distance and the axis of the telescope is directed toward any one of the points of the object, at 95 the same time the pencil is drawn outward until the point touches the paper. The point so marked is the exact projection of the point seen through the telescope. In the same 100 manner the perspective of any number of points of the object can be marked on the paper and by properly uniting the points so marked, an exact perspective drawing or picture of the object viewed is obtained. The 105 telescope is not worked directly with the hand, but by means of the pencil tube n . This latter is held in the hand and raised slightly above the surface of the paper; it is then moved about in different directions until the 110 axis of the telescope points directly to a given point in the object. The pencil is then lowered without causing its axis to deviate from the direction obtained; and the point where 115 it meets the paper, is the position in the perspective drawing of the point viewed.

What I claim as my invention, and desire to secure by Letters Patent, is—

1. A perspectograph comprising a telescope or sighting apparatus mounted so as to be 120 capable of turning in any direction, but with a point of its axis constantly fixed, and a pencil at the extremity of an extensible tube fitted in such manner that the axis of the pencil passes through the fixed point of the 125 telescope, the telescope and the pencil being so connected together that the movements of the one are imparted to the other substantially as and for the purpose hereinbefore described. 130

2. In a perspectograph having a telescope or sighting apparatus and a pencil mounted so as to be capable of rotating at right angles to each other, means such as are herein de-

scribed for connecting the pencil and the telescope together in such manner that the movements of the one are imparted to the other substantially as and for the purpose hereinbefore described.

3. In a perspectograph having a telescope or sighting apparatus and a pencil mounted so as to be capable of rotating at right angles to each other, connecting the telescope and the pencil together in such manner that the movements of the one are imparted to the other, by the employment of a slider capable of being slid along or rotated on a fixed horizontal rod, the axis of which is at right angles

to the axes of the telescope and the pencil, 15 said horizontal rod forming part of a frame or support for the instrument, all arranged and combined so as to operate substantially as described and illustrated.

4. A perspectograph consisting of the combination of a telescope, a pencil, and a slide for conveying the movements of the pencil to and from the telescope. 20
